CLAIM

The ornamental design for a mobile device case, as shown and described.

DESCRIPTION

FIG. 1 is a front perspective view of a mobile device case showing our claimed design thereof;

FIG. 2 is a top plan view of the mobile device case of FIG. 1;

FIG. 3 is a front elevational view of the mobile device case of FIG. 1;

FIG. 4 is a right side elevational view of the mobile device case of FIG. 1;

FIG. 5 is a rear elevational view of the mobile device case of FIG. 1;

FIG. 6 is a left side elevational view of the mobile device case of FIG. 1;

FIG. 7 is a bottom plan view of the mobile device case of FIG. 1; and,

FIG. 8 is a rear perspective view of the mobile device case of FIG. 1.
